UNITED STATES PATENT OFFICE

158,679

CHILD'S SWING

Louis W. Otis, Seattle, Wash.

Application December 4, 1948, Serial No. 150,003

Term of patent 14 years

(Cl. D34—15)

To all whom it may concern:

Be it known that I, Louis W. Otis, a citizen of the United States, residing in Seattle, in the county of King and State of Washington, have invented a new, original and ornamental Design for Child's Swing, of which the following is a specification, reference being had to the accompanying drawing, forming part thereof.

Fig. 1 is a perspective view of a child's swing showing my new design.

Fig. 2 is a side view of the swing.

Fig. 3 is a plan or top view of the same.

I claim:

The ornamental design for a child's swing, as shown.

LOUIS W. OTIS.
